UNITED STATES PATENT OFFICE.

STEPHEN J. POPLAWSKI, OF RACINE, WISCONSIN, ASSIGNOR TO THE ARNOLD ELECTRIC COMPANY, OF RACINE, WISCONSIN, A CORPORATION OF WISCONSIN.

DISPENSER.

Application filed June 28, 1924. Serial No. 722,998.

My invention relates to dispensers and has a number of objects and advantages in view. The dispenser of my invention has, as one of its characteristics, the provision of a closure for the discharge opening in the container so combined with a measuring and discharging element within the container as to uncover the discharge opening as the discharging element places a pocket therein, which contains the material to be discharged, at said opening. The cover is then restored to cover the emptied pocket. The closure and the emptied pocket therein thus prevent the access of moisture to the container through the discharge opening, an important advantage in dispensers of malted milk or other substances that are highly hygroscopic and therefore apt to pack, when moistened.

In accordance with another characteristic of the invention, the closure for the discharge element is movable in an opening direction by mechanism including an actuating element in register with the opening, whereby the closure may be opened by a receptacle placed beneath the opening to receive matter passed through the opening.

In the preferred embodiment of the invention the measuring element is in the form of a wheel having teeth which define a succession of pockets communicable in sequence with the discharge opening, the mechanism that operates the closure being adapted to move it in opening and closing directions that are alternate and to move the wheel in a uniform direction in proper timed relation with the movements of the closure. My invention also comprises the provision of a guard plate adapted to be supported by co-operating shoulders on the container and by extending loosely about the upper end of the shaft, the guard plate being located above the discharge opening so as to prevent access of the material within the container to the discharging pocket.

The dispenser also includes one or more vibrating or movable blades adjacent the material being discharged and means for setting these blades into vibration as the material is being discharged so that no portion of the measured quantity undergoing discharge will remain. These vibrating blades preferably constitute the side walls of the measuring pockets. The means for setting the blades into vibration preferably resides in toothed blocks which are at the radial sides of the

discharge opening to engage the blades as they enter into register with said opening and leave the same.

The invention, in all of its characteristics, will be more fully explained in connection with the accompanying drawing, in which Fig. 1 is a side view of the preferred embodiment of the invention; Fig. 2 is a plan view of the device in the region of the measuring wheel, the casing portion surrounding the wheel being removed; Fig. 3 is a view in partial cross-section on line 3—3 of Fig. 2; Fig. 4 is a view in partial cross-section on line 4—4 of Fig. 5 showing a bottom view of the ratchet mechanism; Fig. 5 is a sectional view on line 5—5 of Fig. 3; Fig. 6 is a plan view of a part of the device showing the casing 23 with the associated levers 22 and 26, the balance of the mechanism being removed; Fig. 7 is a view similar to Fig. 4 showing changed positions of parts of the mechanism; Fig. 8 is a sectional view on line 8—8 of Fig. 5; and Fig. 9 is a perspective view illustrating some of the cooperating parts in separated relation.

The upright cylindrical container 1 has a discharge opening 2 in its bottom wall 3. This opening has a closure in the form of an arcuate spring plate 4 carried on the exterior of the container upon an arm 5 which is in the form of a leaf spring and constitutes the termination of an angular lever 6 mounted to turn upon an upright shaft 7 which is coaxial with the container. By mechanism to be described, the closure 4 is moved in alternate directions to open and close the discharge opening. The spring arm 5 serves to press the spring plate against the margins of the discharge opening to hermetically seal the opening. The closure has an extension 8 which is curled upon the rounded edge of the container bottom.

A flat measuring wheel 9 is formed with teeth 10 which define a circular succession of pockets 11 adapted to be successively placed in register with the discharge opening. This wheel is within the container and turns upon the bottom wall thereof, the teeth ends closely approaching the cylindrical wall of the container in order that the quantities in the pockets may be accurately measured in conjunction with a levelling arcuate plate 12 carried by and within the container above and in register with the discharge opening and pressing upon the

top of the wheel. This plate constitutes a closure for the receiving end of the particular pocket 11 that is placed in register with the discharge opening, and is of limited extent to permit communication between the remaining pockets and the interior of the container in order that they may be filled. The blades 10 also agitate the material within the container, a function which is supplemented by the agitator bar 13 mounted to turn with the wheel. This bar is continued upon both sides of the shaft, each half being spirally twisted to constitute two twisted blades to improve its operation. The plate 12 is supported at its outer edge by a projection 12² on the plate 12 which is adapted to be received in notch 12³ upon the wall 3 and the plate 12 also has an aperture 12' at its inner end adapted to receive the projecting shaft on the upper side of the measuring wheel 9. The cylindrical portion 1 that is above the wheel rests upon the shoulder 12⁴ and holds the lug 12² in the notch.

In the preferred embodiment of the invention, the shaft 7 is turned in a uniform direction and is connected with the wheel to turn it in a like direction. The shaft has a head 14 fixed thereon and received in a recess in the bottom of the wheel, and upon this head there is a pin 16 received in the bottom of the wheel to couple the wheel and shaft. Mechanism is employed to rotate the wheel step by step, each movement of the wheel withdrawing the pocket last emptied from the discharge opening and placing an ensuing and filled pocket in register with this opening. This step by step mechanism includes a ratchet wheel 17 secured upon the lower end of the shaft 7. This ratchet wheel 17 is turned step by step to turn the measuring wheel step by step by means of the actuating pawl 18 carried by the lever 6. The pawl, in turn, is actuated by an arm 19 carried thereby and having a socket 20 receiving the ball 21 upon the lever 22 which is pivoted upon and within the hollow supporting base 23 for the container. The lever 22 has an arm 24 carrying a roller 25 engaging the back of the arm 26 pivoted at its upper end upon the base 23 and below and normally in register with the discharge opening 2. When the shaker or other receptacle which is to receive a measured quantity of material from the container is placed below and in register with the discharge opening 2, the arm 26 is moved thereby to operate the lever 22 and advance a filled pocket into register with the discharge opening in place of the pocket last emptied. During this movement of the wheel, the closure 4 is moved from beneath the discharge opening 2 in the same direction in which the wheel is moved, since this closure is carried by the lever 6 as previously de-

scribed. When the receptacle is moved away from the discharge opening the arm 26 is released to permit the spring 27 to move the arm 6 in an opposite direction to its initial or idle position. As a result of this restoring movement of arm 6 the closure 4 is moved in a reverse direction again to close the discharge opening and to bring the pawl 18 into engagement with a fresh tooth upon the ratchet wheel 17 preparatory to a repetition of the described cycle of operations.

Appreciable momentum is imparted to the measuring wheel. To prevent this momentum from carrying the wheel beyond a single step of movement, I provide a detaining toothed wheel 28 upon the shaft 7. The holding dog 29 is pressed toward this wheel by a spring 30. This spring maintains an extension 31 of the dog in contact with the lever 6. When this lever is turned to uncover the discharge opening the spring 30 causes the dog 29 to follow the movement of the lever and to place the dog in register with the next tooth upon the holding wheel 28. The teeth upon the wheels 17 and 28 are similar in number and position so that when the opening movement of the closure 4 has been effected, the wheel 28 will engage the dog 29 to limit the movement of the measuring wheel to a single step. In the restoring movement of the closure to its closed position, the lever 6 will move the dog 29 away from the wheel 28 so that the measuring wheel may again be moved a step. The teeth 10 are desirably in the form of thin blades of steel that are set into the body of the measuring wheel. Toothed blocks 32 are placed in the container above the radial sides of the discharge opening and in the zone of the measuring wheel. The teeth of these blocks project slightly inside of the circle of rotation of the outer ends of the blades so that the blades are set into vibration or jarred after they come above and leave the discharge opening, whereby material which would otherwise tend to remain upon the blades and other portions of the pocket being emptied is dislodged by the vibration thereof. The blades impact upon the teeth that follow the teeth they escape to jar material loose.

In addition to the advantages of my invention which have been set forth and which are apparent, it will be observed that no hand need touch the material issuing from the dispenser.

Changes may be made without departing from my invention.

Having thus described my invention, I claim:

1. In a dispenser, a container having an aperture in its lower side, said aperture being bounded by a flat seating surface, measuring and discharging mechanism in said container including a rotatable mem-

ber having vibratable partitions, a sliding closure resiliently pressed against said seating surface and common means to actuate said measuring mechanism and said closure.

5 2. In a dispenser, a container having an aperture in its lower side, said aperture being bounded by a flat seating surface, measuring and discharging mechanism in said container including a rotatable member having vibratable partitions, a sliding closure resiliently pressed against said seating surface and common means to actuate said measuring mechanism and said closure, and guide means for said sliding closure to hold the same in position to slide upon said seating surface.

3. In a dispenser, a container having an aperture in its lower side, said aperture being bounded by a flat seating surface, measuring and discharging mechanism in said container having a shaft extending therefrom, said measuring mechanism including a rotatable member having a plurality of resilient blades, a lever rotatively mounted on said shaft to actuate said measuring mechanism step by step, and a sliding closure resiliently mounted on said lever to close said aperture.

4. In a dispenser, a container having an aperture in its lower side, said aperture being bounded by a flat seating surface, measuring and discharging mechanism in said container, including a rotatable wheel having a plurality of resilient blades adapted to align with said aperture, an actuating shaft for said mechanism extending from said container and a ratchet wheel on said shaft to actuate said mechanism, a lever rotatively mounted on said shaft, a sliding closure resiliently supported by said lever and a pawl on said lever for actuating said ratchet and spring means biasing said closure to closed position.

5. In a dispenser, a container having an aperture in its lower side, a measuring and discharging mechanism comprising a rotating element having a plurality of resilient projecting partitions, and means co-operating with said partitions to place in vibration partitions adjacent both sides of said aperture during discharge.

6. In a dispenser, a container having an aperture in its lower side, measuring and discharging mechanism in said container comprising a plurality of resilient partitions, and means for placing certain of said resilient partitions in vibration to effect complete discharge of the material adjacent said partitions.

7. In a dispenser, a container having an aperture in its lower side, measuring and discharging mechanism in said container comprising a rotating element having a plurality of resilient projecting partitions, means for actuating said rotating element to

successive positions over said aperture, and a plurality of obstructions over which said resilient partitions snap to place them in vibration when adjacent said aperture.

8. In a dispenser, the combination comprising a container having a flat bottom and an aperture therein, a shaft journalled in said bottom, a rotating measuring element having a plurality of projecting partitions fitting against said bottom, means for actuating said measuring element to successive positions where said partitions align with said aperture, and means for placing one of said partitions in vibration when adjacent said aperture.

9. In a dispenser, the combination comprising a container having a flat bottom and an aperture therein, a shaft journalled in said bottom, a rotating measuring element having a plurality of projecting partitions fitting against said bottom, means for actuating said measuring element to successive positions where said partitions align with said aperture, means for placing said partitions in vibration when adjacent said aperture, and means for levelling the charge between said partitions and separating said charge from the balance of the material in said container.

10. In a dispenser, a container having an aperture in its bottom, a shaft journalled in said bottom, measuring and discharging mechanism in said container actuated by said shaft, ratchet mechanism on said shaft to actuate the same step by step, said measuring and discharging mechanism including a plurality of resilient blades and means for placing one of said blades in vibration when adjacent said aperture, and means actuated by a container placed beneath said aperture to actuate said ratchet mechanism.

11. In a dispenser, the combination of a container having a dispensing aperture, a measuring and discharging device in said container, having a plurality of resilient partitions movable past said aperture, means for placing a resilient partition in vibration when it reaches a position adjacent said aperture, a shield for preventing access of material in said container to parts of said device above said aperture, step by step mechanism for bringing said partitions successively into registry with said aperture to discharge material, and an external sliding closure for said aperture actuated to open position by said mechanism.

12. In a dispenser, the combination of a container having a flat bottom, with a shaft journalled in said bottom, said container having a discharging aperture in said bottom, a measuring wheel mounted on said shaft, and a plurality of resilient blades on said wheel, said blades being adapted to register with sides of said opening.

13. In a dispenser, the combination of a

- container having a flat bottom, with a shaft journalized in said bottom, said container having a discharging aperture in said bottom, a measuring wheel mounted on said shaft, a plurality of resilient blades on said wheel, said blades being adapted to register with sides of said opening, a lever carried by said shaft, and a sliding closure for said aperture resiliently mounted on said lever.
14. In a dispenser, the combination of a container having a flat bottom, with a shaft journalized in said bottom, said container having a discharging aperture in said bottom, a measuring wheel mounted on said shaft, a plurality of resilient blades on said wheel, said blades being adapted to register with sides of said opening, and a plurality of obstructions over which said blades slide to place said blades in vibration.
15. In a dispenser, the combination of a container having a flat bottom, with a shaft journalized in said bottom, said container having a discharging aperture in said bottom, a measuring wheel mounted on said shaft,
16. In a dispenser, the combination of a container having a flat bottom, with a shaft journalized in said bottom, said container having a discharging aperture in said bottom, a measuring wheel mounted on said shaft, a plurality of resilient blades on said wheel, said blades being adapted to register with sides of said opening, a plurality of obstructions over which said blades slide to place said blades in vibration, step by step mechanism for actuating said shaft, and means actuated by placing a receptacle under said aperture for actuating said step by step mechanism.

In witness whereof, I hereunto subscribe my name.

STEPHEN J. POPLAWSKI.
